ART OF PAPER-MAKING

Floyd R. Graham, South Hadley Falls, Mass., assignor to American Tissue Mills, Holyoke, Mass., a corporation of Massachusetts

Application July 15, 1932, Serial No. 622,655

1 Claim. (Cl. 92—69)

This invention relates to improvements in the paper manufacturing art and is directed more particularly to improvements in the method of manufacturing papers for decorative purposes 5 and the products thereof.

The principal objects of the invention are directed to the provision of a method of making decorative paper which is of novel form so as to be adapted for general decorative purposes. 10 Various novel features and advantages of the invention will be more fully hereinafter referred to in connection with the following description of the present preferred form of the invention and for purposes of disclosure reference will be made 15 to the accompanying drawing wherein;

Fig. 1 is a plan view of a portion of a sheet of paper having the novel features of the invention incorporated therein.

Fig. 2 is a sectional view of the sheet shown in 20 Fig. 1 taken on the line indicated by the numeral 2.

Fig. 3 is a portion of a streamer showing a modified form of the invention, and

Fig. 4 is a sectional elevational view showing 25 superposed strips or webs which are fluted.

Referring now to the drawing in detail the method of the invention will be more fully described.

In Fig. 1 there is represented a portion of a 30 sheet of crepe paper embodying the novel features of the invention. This has spaced apart longitudinal extending portions 4, which are creped transversely. Intermediate fluted portions 6 are provided with alternate ridges and 35 grooves disposed transversely between the non-fluted creped portions 4.

In carrying out the invention it is desirable to employ crepe paper and to form the flutes or alternate grooves and ridges so that they extend 40 generally in the direction of the creping. The alternate ridges 7 and grooves 9 may be formed in the paper by passing the same between coacting toothed members such as gears. These may exert more or less pressure and in that way provide 45 the grooves shown.

According to the preferred form of the invention a sheet or web of paper may be provided with creping which extends in one direction such as 50 transversely thereof, while suitable rolls may provide the alternate grooves and ridges which terminate in spaced relation so as to form the creped non-grooved and the relatively less creped and grooved sections alternately arranged, with the grooves running in the direction of the creping.

As stated, the paper sheet or a strip is extensible and elastic longitudinally thereof, while at the same time certain sections thereof are not only ornamented by the grooves, but these at the same time provide a fullness so that the paper is easily 60 and readily manipulated.

Fig. 3 shows a modified form of the invention in which there is employed one or more strips 2 of crepe paper or the like wherein the creping extends transversely thereof. According to the 65 method of the invention a single sheet or strip of crepe paper may be run through coacting toothed members such as gears which act on opposite side edges thereof or two or more of such creped strips are run through gears simultaneously and in superposed relation.

By employing the crepe paper mentioned and which is more or less flexible, it is distorted more or less by the ridges and its grooves so that its edges are flexible and there is a fullness at the 70 sides of the strip as compared with the central portion thereof. The central portion of the strip is stretchable to some extent and more or less elastic because the strip is creped while the longitudinal edges are less elastic but are quite flexible 75 because they are fulled, so to speak.

The fluted sides of the strips formed by the ridges and grooves not only ornament the strips but allow the strip to be bent at angles and curved as at a corner of a decoration without the necessity of overlapping portions of the strip at the corners as is now customary. In decorating with the strip it is possible to twist the strip from end to end to obtain a true spiral effect because the central or stretchable portion of the strip acts as 80 a support while the edges are sufficiently flexible 85 to assume the spiral formation.

As stated, it is desirable in some cases to superpose two or more strips as shown in Fig. 4 and to provide the fluted edges. The fluting operation 90 on the marginal edges of superposed strips tends to unite the edges so that the plurality of strips appear as a unitary strip consisting of one or more colors if this is desired.

It is often desirable to provide a streamer with 100 different colors on opposite sides thereof and which is not possible ordinarily without pasting strips together. According to this invention it is possible to secure separate strips together which may be of different color to provide a unitary strip 105 having different colors on its opposite sides. Altogether the streamer of the invention is well adapted for decorating purposes in general because it is not only flexible, but is sufficiently stretchable so that it may be hung in various 110

ways without destroying or injuring the artistic appearance thereof.

The strip, of course, may be of various widths and the grooves and ridges may extend inwardly 5 from the marginal edges to any desired depth so as to leave a central longitudinal uncorrugated portion of a desired width which extends longitudinally of the strip. The central creped portion is important because the strip by being 10 formed of crepe paper may be made relatively stretchable and elastic throughout the central zone as compared with the fulled marginal edges. The central longitudinal crepe zone acts as a support for the fulled marginal edges formed by the 15 alternate grooves and ridges. As has been stated, the strip of the invention is much more flexible than the well-known crepe strip and lends itself more readily to decoration.

According to the invention the ridges and 20 grooves extend transversely of the sheet or strip as does the creping. The ridges and grooves terminate so as to provide the non-fluted sections 4 therebetween.

The previously creped paper lends itself readily 25 to the grooving operation because of course the creped paper is more or less stretchable so that it may be offset or distorted without injury thereto.

The non-grooved portions and grooved portions 30 arranged as they are provide a decorative effect which is desirable. At the same time the paper whether in sheet or strip form is very flexible

so that it may be folded, bent, curled and otherwise manipulated around and upon objects to create ornamental effects.

It may be said that the creping of the paper causes the paper to be more or less firm and elastic, while the grooves provided therein provide a fullness in certain parts thereof. Since the groove portions are separated from one another, the grooving does not destroy the desired stretchability of the paper, but does enhance the appearance thereof and provides a fullness or fluffiness, whereby the paper is adapted for decorative purposes and as a whole is not likely to be injured in its manipulation.

Having described the invention in the form at present preferred, what it is desired to claim and secure by Letters Patent of the United States is:

The method of producing paper adapted for ornamental purposes which consists in, fluting the opposite longitudinal sides only of superposed strips of crepe paper to provide strips having relatively flat central non-fluted sections and flexible distorted edge portions, the said crepe paper having the creping extending transversely thereof and said fluted sections comprising alternate 100 ridges and grooves extending in parallelism with said creping, the grooves and ridges of one strip interfitting with the grooves and ridges of the strip on which it is superposed whereby the relatively flat central non-fluted sections of the strips 105 are in close adjacency.
